[57] CLAIM

The ornamental design for a display unit and light fixtures therefor, as shown and described.

DESCRIPTION

FIG. 1 is a front elevational view of a display unit and light fixtures therefor showing our new design;
FIG. 2 is a side elevational view taken from the right of FIG. 1, the left side being a mirror image thereof;
FIG. 3 is a bottom view of the design of FIG. 1.
The top and rear surfaces of the design of FIGS. 1 through 3 are plain and unornamented.

FIG. 1

FIG. 2
